ADJUSTABLE SUPPORT FOR BUILDING
STRUCTURES

Howard T. Crosby, Los Angeles, Calif.

Application August 5, 1939, Serial No. 288,601

2 Claims. (Cl. 72—77)

This invention relates to supports for building structures, and particularly to means for adjustably supporting the floor structure of a building.

In building construction it is common practice to support girders upon wooden posts which in turn rest upon wooden blocks mounted on concrete piers. Due to inequalities in the settling of the different piers, shrinkage of the soil, shrinkage and warping of the lumber and many other factors, adjustment of the pier posts is rendered necessary to prevent cracked plaster, jammed doors, creaking floors, and other symptoms of unequal bearing upon the pier posts. This has been accomplished in the past by merely wedging shingles under the pier posts as necessary to raise the individual posts.

It is an object of the present invention to provide a pier post which may be easily adjusted as settling, shrinking, warping, and the like, take place.

It is another object of this invention to provide a pier post which can be adjusted readily by means of a small wrench or the like by unskilled persons.

It is a further object of the invention to provide an adjustment for pier posts which may be readily installed in pre-existing structures without extensive alteration.

It is a further object of the invention to provide a pier post which can be used satisfactorily in localities where earthquakes and windstorms exert excessive side thrusts upon building structures.

A still further object of the invention is the accomplishment of the above objects by means of a device which is simple, cheap, and easy to manufacture and install.

This invention possesses many other advantages and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of the invention is best defined by the appended claims.

Referring to the drawings:

Figure 1 is a perspective view showing one form of adjustable support contemplated by the present invention.

Figure 2 is a vertical sectional view through the device.

Figure 3 is a transverse section taken on line 3—3 of Figure 2.

Figure 4 is a bottom plan view of the base plate constituting part of the device.

Figure 5 is an elevational sectional view of a modified form of the invention; and,

Figure 6 is a transverse section taken on line 6—6 of Figure 5.

In Figures 1 to 3 of the drawings, one form of the invention is shown installed beneath a portion of the floor structure of a building. The device includes a base plate 10 mounted on a concrete pier 11. The plate 10 is preferably mounted on the concrete pier at the time of forming said pier, and the underside of said plate is provided with a roughened or uneven surface 12 which is imbedded in the concrete, whereby upon hardening of the pier, said plate is anchored against lateral displacement relative thereto which might otherwise be caused due to forces, such as are encountered through earthquake shocks.

An adjustable plate 15 is adjustably mounted for movement toward and away from the base plate 10 through the agency of a plurality of adjusting bolts 16 passing through openings 17 in said plate and having their lower ends bearing against the base plate in sockets 18 provided therein. Said bolts carry nuts 20 which bear against the underside of the adjusting plate in recesses 21 formed therein. The sides of said recesses correspond to the polygonal sides of the nuts so as to prevent their turning upon rotation of the bolts therethrough to effect a raising or lowering of the plate 15. The upper ends of the adjusting bolts are provided with heads 22 by which they may be conveniently adjusted with a wrench or the like.

In order to positively insure against dislodgement of the adjusting plate and adjusting bolts from the base plate due to severe shocks, such as might be encountered in earthquakes, a rod 23 is anchored in the concrete pier, and extends through openings in both the base plate 10 and the adjusting plate 15, said rod 23 permitting movement of the adjusting plate toward and away from the base, but preventing lateral displacement thereof.

A load transmitting member or post 24, shown as being of metal tubular construction, is mounted upon the adjusting plate 15 and has its upper end bearing against another plate 25, nailed or otherwise secured to a girder of the floor structure, as shown at 26 in Figure 2. In order to prevent lateral displacement of the upper end

of the post, the plate is provided with a depending portion 27, telescoping into the upper end of said tube. The lower end of the post is restrained against appreciable lateral displacement by an extended portion 28 on the adjusting plate. Furthermore, the extended portion 28 is co-operable with the lower portion of the post to prevent said post against appreciable angular displacement with respect to the adjusting plate.

In case of intense shocks, such as are encountered in earthquakes, it is desirable to have a certain degree of flexibility in the device, but at the same time positively prevent undesirable displacement between the various parts. Such yieldability is effected in the present instance by providing relatively loose joints between the various parts of the device. For instance, it will be observed that spaces are provided between the ends of the post 24 and the portions 27 and 28 of the respective plates 25 and 15. Relatively loose joints are also provided between the adjusting plate 15 and the adjusting bolts and nuts, as well as between the bolts and walls of the sockets 18 of the base plate into which they enter.

As shown in Figure 1, the load transmitting member 24 may be rigidly secured to the floor structure as by providing braces 30 between the said member and the girders and joists 31. One end of these braces is secured to a sectional collar 29 clampedly secured to the member 24, and their other ends may be nailed or otherwise suitably secured to the girders and joists.

The operation of this form of the invention should be clear. If for any reason it becomes necessary to alter the distance between the girders 31 and the pier 11, due to settling, shrinkage or warping of any of the parts of the structure, adjustment is had by turning the bolts 16 with a wrench applied to the heads 22 thereof. Excessive lateral movement of the girder 31 with respect to the pier 11 is prevented by the braces 30 and the portions 27 and 28, all tending to prevent movement of plate 15 with respect to the girder 31. Plate 15 is prevented from moving with respect to the pier 11 by the rod 23, and by the engagement of the adjusting bolts 16 in the sockets 18 of the base plate 10.

In the form of the invention shown in Figures 5 and 6, a base plate 40 is mounted upon a concrete pier 41, and an adjusting plate 42 is mounted for movement toward and away from the base plate through the agency of adjusting bolts 43 similarly to the arrangement heretofore described. This form of adjustable support is adapted for use primarily where wooden pier posts are utilized in a building structure. One such post 44 is shown supported upon the adjusting plate 42, its lower end being secured

against lateral displacement with respect thereto by lugs 46 provided on said adjusting plate, and nails 45 passing through said lugs into the post. The upper end of the post may be nailed or otherwise suitably secured to a girder 47 as by the braces 47'.

As in the form heretofore described, assurance against dislodgement of the adjusting plate 42 and bolts 43 with respect to the base plate is prevented by the rod 48 anchored in the pier 41 and slideable through an opening in the adjusting plate 42. The anchor rod 48 extends into a bore 49 in the pier post 44.

If it is desired to utilize a metal tubular pier post in conjunction with the adjustable pier block construction shown in Figures 5 and 6, a member such as 25 in the form shown in Figure 1 may be positioned between the lugs 46 on the adjusting plate 42, with the tubular portion thereof extending upwardly to receive the lower end of the tubular post.

The adjustable pier block construction, Figures 5 and 6, may be readily applied to pre-existing installations. In such a case, the wooden block, commonly employed between the lower end of the post and the pier, is removed and the device slid into place. It will be noted in Figure 6 that the lugs 46 extend around three sides only of the post 44 to permit such insertion. Of course, the rod 48 would have to be omitted from constructions in which it is desired to perform this substitution.

I claim:

1. An adjustable supporting structure for buildings including a base, an adjusting member, means mounting said member for movement toward and away from said base, an elongated member extending from said base and cooperative with said adjusting member for holding it against lateral displacement with respect to said base, a pier post mounted on said adjusting member intermediate said member and the floor structure of a building, and means securing the upper end of said pier post to said floor structure.

2. An adjustable supporting structure for buildings including a base, an adjusting member, means mounting said member for movement toward and away from said base, an elongated member extending from said base and cooperative with said adjusting member for holding it against lateral displacement with respect to said base, a pier post mounted on said adjusting member intermediate said member and the floor structure of a building, means securing the upper end of said pier post to said floor structure, and a plurality of braces connecting said pier post with said floor structure.

HOWARD T. CROSBY.
